UNITED STATES PATENT OFFICE.

JOHN J. BATMAN, OF SUNBURY, PENNSYLVANIA.

DREDGING-MACHINE.

SPECIFICATION forming part of Letters Patent No. 620,635, dated March 7, 1899.

Application filed March 23, 1898. Serial No. 674,857. (No model.)

To all whom it may concern:

Be it known that I, JOHN J. BATMAN, a citizen of the United States, residing at Sunbury, in the county of Northumberland and State 5 of Pennsylvania, have invented new and useful Improvements in Dredging-Machines, of which the following is a specification.

This invention relates to certain new and useful improvements in dredging-machines, 10 the object of the invention being to provide a hydraulic suction-dredge of improved construction in which the suction-tube can be positioned as desired, said tube having at its inlet-opening or lower end an agitator or 15 screen of such construction that the material upon which the dredge is working may be loosened and separated to prevent the clogging up or stoppage of the suction-pipe.

A further object of the invention is to provide means for operating or moving the agitator and screen over the mouth of the suction-pipe, so that the position of the same 20 may be varied and reciprocated, and also generally to improve and simplify the construction of the dredge and its parts, so that the suction-pipe may be readily moved as desired, the shifting of the suction-pipe in no wise interfering with the effective operation 25 of the agitator and screen.

30 In the accompanying drawings, Figure 1 is a side elevation of the dredge; Fig. 2, a detail view of the agitator and screen, its parts being shown separated or in detail; and Fig. 3 is a front elevation of the dredge, showing 35 the suction-pipe with agitator and screen and mechanism for operating the same.

This invention is designed more especially for dredging in rivers or waters for the purpose of removing the bed to form channels or 40 for the purpose of sinking shafts to bed-rock in dredging for minerals, especially gold, and the main or leading feature of my invention—to wit, the agitating chain and screen—is applicable to many forms of suction-dredges.

45 Upon a suitable float is mounted a centrifugal pump A, which is driven in the usual manner, the same having connected thereto a discharge-pipe A' and the suction-pipe, the suction-pipe having suitable swivel connections which admit of the desired range of adjustment. The suction-pipe may be made of several sections, which are coupled together,

B referring to the section which is attached to the inlet-pipe of the centrifugal pump, and this section has suitably connected thereto a 55 casting or fixture with a stub-axle, upon which are mounted a sprocket-wheel b and hand-wheel b', which is rigidly connected to the sprocket-wheel, and the upper end of the tube or pipe B may have connected thereto 60 an angle-joint or curved section, which carries a fixture designed to support shafts c c', there being mounted on the shaft c a sprocket-wheel and a pinion, which are rigidly connected to each other, the pinion meshing with a pinion 65 or gear c² on the shaft c', there also being attached to said shaft a sprocket-wheel d. Over the sprocket-wheels b b² are passed chains b³ b⁴, said chains being connected to each other by bars, one of the bars having threaded ends 70 and a turnbuckle for the purpose of adjusting the chain-sections. The lower section C of the suction-pipe carries at its lower end a shaft e, mounted in suitable bearings and provided with sprocket-wheels e', positioned to 75 one side of the suction-pipe, and over these sprocket-wheels passes the agitator and screen E, the upper ends of which are attached to bars which connect with the section of chain which passes over the sprocket-wheel d, the 80 connecting-bars on one side of the tube having adjusting means. The bars just mentioned have their lower ends spread for engagement with the ends of the agitator chain and screen. 85

The agitator chain and screen is made up of bars f, upon which are strung links f' f². Arranged alternately and between said links are sleeves f³. The links f' have outwardly-projecting spurs or teeth which are adapted 90 to enter the soil and loosen the same, and between the links and sleeves there are provided openings which are of such size as to admit the material through the meshes of the chain to the suction-tube, and this chain may be 95 moved either to bring a different part thereof over the mouth of the suction-tube or it may be reciprocated by oscillating the hand-wheel b' on the tube B, it being obvious that when said hand-wheel is oscillated motion will be 100 imparted to the agitating chain and screen through the mechanism hereinbefore referred to. If desired, the hand-wheel b' may be operated by mechanical means.

To the upper end of the suction-pipe in any suitable manner is attached a trussed bar G, the end of which is provided with an eyebolt for connecting thereto a pulley forming a part 5 of a tackle which extends therefrom to the float or scow, and by drawing upon the tackle and paying out, or vice versa, upon the tackle H, which is also connected to the float and to a bail h, attached to the suction-pipe C, the 10 angle of the suction-pipe may be varied with respect to the pipe-section B. When it is desired to raise or lower the suction-pipe, it can be accomplished by operating the tackle I, one end of which is attached to the elbow-section 15 of the suction-pipe, the other end being secured to a mast or upright I'.

The discharge-pipe A', which is connected to the centrifugal pump, may lead where desired as to floats or to suitable separating 20 mechanism when used for mining purposes.

Having thus described my invention, what I claim as new, and desire to secure by Letters Patent, is—

1. In combination with the suction-pipe of 25 a dredge, a flexible agitator and screen positioned over the mouth or inlet-opening of the suction-pipe.

2. In a dredging-machine, a suction-pipe having sprocket-wheels carried thereby, a 30 flexible agitator and screen mounted thereon, and means for moving the agitator and screen, for the purpose set forth.

3. In a dredging-machine, the combination 35 with the suction-pipe thereof, of a flexible agitator and screen positioned over the open end

of the pipe and provided with outwardly-projecting spurs, substantially as shown.

4. In combination with the suction-pipe of a dredge, of a flexible agitator and screen mounted so as to lie over the mouth or inlet- 40 opening of the suction-pipe, and having outwardly-projecting spurs or teeth, means for reciprocating the agitator and screen embodying flexible connections, guides therefor and adjusting-bars, substantially as shown and 45 for the purpose set forth.

5. In a dredging-machine, the combination with the suction-pipes connected to a centrifugal pump, means for adjusting or changing the position of said pipes comprising three 50 sets of tackles, the adjusting-ropes thereof extending to the float, couplings which admit of varying the position of the pipe-sections, a flexible agitator and screen positioned over the mouth or inlet-opening of the suction-pipe, connections extending therefrom to a gear mounted on the suction-pipe, gears meshing with each other and gearing embodying flexible connections extending to a wheel 55 which when operated will move the flexible agitator, substantially as shown and for the purpose set forth.

In testimony whereof I have hereunto set my hand in presence of two subscribing witnesses.

JOHN J. BATMAN.
